UNITED STATES PATENT OFFICE.

JAMES I. AYER, OF CAMBRIDGE, MASSACHUSETTS, ASSIGNOR TO SIMPLEX ELECTRIC HEATING COMPANY, OF BOSTON, MASSACHUSETTS, A CORPORATION OF MASSACHUSETTS.

AUTOMATIC INDICATOR OR THERMOSCOPIC SIGNAL FOR HEATED TOOLS AND VESSELS.

No. 884,973.

Specification of Letters Patent.

Patented April 14, 1908.

Application filed May 16, 1907, Serial No. 374,067.

To all whom it may concern:

Be it known that I, JAMES I. AYER, a citizen of the United States, residing at Cambridge, in the county of Middlesex and State 5 of Massachusetts, have invented an Improvement in Automatic Indicators or Thermoscopic Signals for Heated Tools and Vessels, of which the following description, in connection with the accompanying drawings, is 10 a specification, like letters on the drawings representing like parts.

This improvement relates to the class or kind set forth at length in my Patent No. 854,013, my present invention not being necessarily dependent upon electric current however.

Various kinds of articles, and particularly electrically heated domestic utensils, such as electric flat-irons, which give no visual evidence in themselves as to whether heat is being applied or not, often do damage or are damaged, simply because of the fact that their thermal condition is not known. And on the other hand, the operator is often annoyed to find the article still cold, when he or she had supposed the current was on or heat had otherwise long since been applied, where as in fact it had not been applied.

Accordingly my present invention provides a heat - retaining, signal - protecting, thermoscopic signal-lever, or mechanically displayed but heat operated signal or indicator, which automatically gives notice whenever the desired temperature is present 35 in the tool, vessel or other article.

Referring to the drawings, in which I have shown one out of many contemplated embodiments of my invention, Figure 1 is a side elevation of my invention applied to a flat-iron; Fig. 2 is a plan view thereof; and Fig. 3 is a sectional detail.

For convenience of explanation, I have illustrated my signal or notice-giver in connection with a usual flatiron, comprising a 45 base 1, 2, and handle 3, the part 1 containing the usual electric resistance wires as usual for heating the tool. While my signaling device may be located according to convenience or preference, I prefer to place it conspicuously at the front and yet sheltered, and therefore I have deflected the front handle-support at 4 and beneath this protector is a 50 heat-transmission and retention box or housing 5, open at the top, in which is pivoted at

6 a signal lever 7, preferably having a boss or 55 lifting lug 8 close to the fulcrum 6 to be engaged by the thermal lifter or actuator 9. The latter consists of two strips 10 and 11 of dissimilar metals soldered or otherwise secured flat upon each other lengthwise, in 60 well-known manner, as in heat gages, watch balances, etc., the lower strip or bottom part of the laminæ or laminated actuator 9 having the higher coefficient of expansion. This actuator 9 is made fast at 12 to a block 13 65 at the rear end of the box and projects forward in pushing or lifting contact with the signal lever 7. The latter may have a ball-shaped head or other striking display part, being shown as provided with bright colored 70 disks 14, 15 set at right angles to each other.

When the flat-iron is cold, the parts remain as shown in full lines in Fig. 3, but when heat is applied, and the temperature begins to approximate working-conditions, 75 the lifter or actuator expands, and, because of its bimetal laminæ, it curls upwardly at its forward end and raises the signal 14, 15 to its dotted position Fig. 3, and as shown in Fig. 1, thereby giving visual notice that 80 the iron is properly heated and ready for work. The construction shown is such that only a small upward movement of the laminar actuator 9 is sufficient to force the signal lever 7 from its concealed horizontal position 85 to its upright displayed position. This provides at a glance a visual signal showing that the iron is actually in service or provided with heat. The signal-lever remains raised so long as the temperature of the iron continues at or above the predetermined minimum point, which was necessary first to raise the lever to its vertical position. A stop-part or lug 16 on the housing is in position to prevent the lever 7 from rising beyond 90 its dotted line position Fig. 3, so that it can never reach truly vertical balanced position, and hence must always fall by gravity when the tool cools and the actuator assumes again its full line position Fig. 3.

The stop 16 and boss 8 cooperate with the end of the actuator or laminated member 9 to keep the signal lever steady and prevent vibration when the laminated member has been curved by the action of the heat into 105 its dotted line position, Fig. 3. When thus curved, the extremity of its movable end abuts against the face of the boss 8 and

presses the lever 7 in non-vibrating or non-movable position against the stop 16, so that as the flat-iron is shoved rapidly back and forth in the process of ironing, the signal lever will not vibrate or rattle.

The casing or box coöperates in maintaining normal temperature conditions about the signal actuator by preventing cooling air currents from reducing its temperature, 10 and hence gives to the signal certainty of position and definiteness of results, while also serving as a protecting receptacle for the lever when lying parallel to the laminar actuator.

15 As already intimated, there is a wide variety of shapes and arrangements in which my invention may be embodied. The actual movement of the signal serves to attract the eye more definitely than the less obtrusive 20 glow of the lamp in my patent before mentioned and moreover renders the signal available in connection with articles which are heated otherwise than by electricity; and this feature of providing movement may be 25 availed of for securing still further conspicuity, as by closing a circuit and lighting the signal when raised. My patented signal above mentioned shows simply whether the current is on or off, whereas the present 30 signal shows whether the iron is operatively heated or not. It flaunts its signal when the working heat is attained. It will be understood that the greatest precision and sensitiveness are secured, according to the 35 length of the laminar actuator, the proportion and composition of its two metals, the extent of contacting surface of the heat convector block, and the arrangement and shape of the signal-carrying member.

40 Having described my invention, what I claim as new and desire to secure by Letters Patent is,

1. The combination with an article of the kind described, having a portion to be heated, of a thermal lifter fast at one end and expandible under the influence of the heat of said article, and a signal lever pivoted close to the free end of said lifter and normally ly-

ing lengthwise over the same when the latter is cold, extending from one end at said 50 pivot to the opposite free swinging end adjacent the fast end of the lifter, the free end of the lifter engaging said lever close to the pivot, to swing the lever from said overlying horizontal position to a raised vertical position. 55

2. The combination with an article of the kind described, having a portion to be heated, of a laminated member fast at one end and arranged to move upwardly at its other 60 end when heated, and a signal lever pivoted close to said movable end and normally lying lengthwise over said laminated member when the latter is cold, said lever being provided adjacent its pivot with a lifting boss 65 projecting against the laminated member, the extreme end of the laminated member extending when cold between the pivot of the lever and said boss.

3. The combination with an article of the kind described, having a portion to be heated, of a laminated member fast at one end and arranged to curve upwardly at its other end when heated, a signal lever pivoted close to the latter end and overlying said member 75 lengthwise, the free moving end of the signal lever normally resting over the fixed end of the laminated member and the movable end of the laminated member normally resting close to the pivot of the signal lever, a fixed 80 stop against which the signal lever is moved when indicating maximum heat, said signal lever having a boss close to its pivot facing toward the laminated member, and the latter having such a length that when extended 85 and curved by the action of the heat its end will engage against said boss and hold the lever against said stop.

In testimony whereof, I have signed my name to this specification, in the presence of 90 two subscribing witnesses.

JAS. I. AYER.
